To all whom it may concern:

Be it known, that I, Viola T. Howard, a citizen of the United States of America, residing at Saylesville, county of Providence, State of Rhode Island, having invented a new, original, and ornamental Design for a Necktie Holder, of which the following is a specification, reference being had to the accompanying drawing, forming a part thereof:

Fig. 1 is a top plan view showing my new design for a necktie holder; and

Fig. 2 is a side elevation thereof.

While the initial W is shown in the drawing it is understood that other initials may be similarly incorporated.

I claim:

The ornamental design for a necktie holder, substantially as shown and described.

VIOLA T. HOWARD.
